CLAIM

The ornamental design for a soft drink dispenser, as shown and described.

DESCRIPTION

FIG. 1 is a perspective view of a soft drink dispenser showing my new design;

FIG. 2 is a front view thereof;

FIG. 3 is a right side view thereof, the left side view being a mirror image thereof;

FIG. 4 is top view thereof;

FIG. 5 is a bottom view thereof; and,

FIG. 6 is a back view thereof.

Broken lines indicate boundaries of regions that form no part of the claimed design.
